APPARATUS FOR MAKING FRENCH SEAMS

Charles Seaman, Jamaica Estates, N. Y.

Application January 17, 1942, Serial No. 427,120

16 Claims. (Cl. 112—136)

This invention relates to an apparatus for making a French seam. More particularly, this invention relates to a sewing machine, and particularly to an attachment for a sewing machine, for producing a French seam.

The nature and objects of the invention will become clear from the following specification, appended claims, and accompanying drawings forming a part of this specification and wherein:

Figure 1 is a top plan view of a sewing machine (the sewing machine head being omitted for clarity) embodying the principles of the invention;

Figure 2 is a side elevation of the sewing machine shown in Figure 1, with the sewing machine head partly broken away;

Figure 3 is a front elevation of the sewing machine shown in Figure 1, with the sewing machine head broken away;

Figure 4 is a perspective view of the folder and presser foot of the attachment;

Figure 5 is a perspective view illustrating the material at the various stages of the operation as it is fed through the sewing machine;

Figure 6 is an end view of the folder and shows the position of the material with respect thereto;

Figure 7 is a section taken on the line 7—7 of Figure 4;

Figure 8 is a section taken on the line 8—8 of Figure 4;

Figure 9 is a section of the material after it has been stitched;

Figure 10 is an end view of the material shown in Figure 8 after it has been unfolded or opened up; and

Figure 11 is an end view of the final material.

In accordance with the principles of the instant invention, the two materials, which are to be joined by a French seam, are stitched together on the right side in the usual manner, and then trimmed closely. The thus-seamed material is then turned or folded about the seam so that the raw edges are disposed between the upper and lower plies and thereby concealed. In this condition, the material is stitched on the wrong side, the stitches passing through the upper and lower plies, whereby the raw edges are concealed, and, when the seamed material is unfolded or opened up, the stitching is concealed.

The joining of the two materials on the right side may be effected in any of the well-known standard sewing machines and the trimming of the seam may be effected in any suitable manner. In the preferred embodiment of the invention, the trimming of the seam is effected by provid-

ing the standard machine with a knife which, in an operation continuous with the production of the seam, also trims the seam. Sewing machines provided with the cutting (trimming) device are well known and standard in the art, and, since the particular details thereof form no part of this invention, a detailed description thereof is not necessary.

After the two materials have been joined together by a seam and the seam closely trimmed as previously mentioned, it is introduced and fed through a folder which, as will hereafter be more fully explained, folds the seamed material about the seam therein so that the raw edges of the seam will be disposed between an upper ply and a lower ply formed by the materials joined by the seam. The folder is mounted and positioned on the sewing machine so that it will present the folded material in proper position to be received by the presser foot and stitched by the needle as it is fed through the path thereof. The presser foot is provided with means which is adapted to engage the exposed edge seam of the folded material and maintain the same in uniform laterally spaced relationship with respect to the path of travel of the needle as the folded material is fed through the machine, whereby uniform stitching is secured. The folder is adjustably mounted with respect to the presser foot whereby it may be adjusted to the desired position, either longitudinally or transversely with respect to the presser foot. The folder is also so mounted whereby it may be, by a simple manual operation, moved from its normal operating position and rendered ineffective or inoperative so that the machine can be used for normal stitching. When the sewing machine is to be used for normal stitching, the presser foot, which constitutes one feature of the attachment, is removed and a normal standard presser foot substituted in place thereof.

The attachment constituting the instant invention may be attached to a standard sewing machine without in any way mutilating, destroying or indeed changing the standard sewing machine. Likewise, the attachment may be rendered ineffective by the simple operation previously described so that the standard machine may be used for usual sewing operations.

In order to more fully explain applicant's invention, reference will now be had to the drawings showing an illustrative embodiment of applicant's invention and wherein the reference numeral 10 designates a standard sewing machine head carried on a work support 12 in the usual

manner. The sewing machine head 10 is provided with a needle bar 14 which carries a needle 16. The needle bar 14 is vertically reciprocated in the usual manner. The head 10 is also provided with the usual spring-pressed presser foot bar 18 on which the presser foot 20, hereinafter more fully explained, is mounted. The presser foot bar 18 is of the usual type and may be elevated and lowered by proper manipulation of the hand lever 22. The presser foot 20 cooperates with feed dogs 24 which pass through slots 26 in a cover plate 28 provided in the work support 12. The feed dogs 24 are actuated by a conventional four-motion feed-actuating mechanism (not shown). Except for the specific construction of the presser foot 20 hereinafter more fully explained, the aforementioned details and features of construction are part of a standard sewing machine.

The presser foot 20 is provided at its upper end with a channeled lug 30, which is adapted to receive the presser foot bar 18 and be secured in position thereon by a set screw 32. At the opposite end, the presser foot 20 is bifurcated to produce toes 34 and 36 separated by a slot 38 through which the needle 16 passes.

To properly maintain the material in uniform laterally spaced relationship with respect to the needle so that during the stitching operation a uniform line of stitching (with respect to at least the edge of the material) is secured, the presser foot 20 is provided with a guide, generally designated by the reference numeral 40. As shown in Figures 4 and 8, the guide 40 comprises a spring arm 41, which is secured at its upper end to the presser foot 20 in any suitable manner, as, for example, by soldering. The spring arm 41 is provided at the opposite end with a substantially inverted J-shaped member, which is adapted to be positioned on the toe 36. As shown in Figures 4 and 8, the long arm 42 of the inverted J-shaped member is positioned adjacent the right side (see Figure 3) of the toe 36 so that it will continuously engage, and thereby uniformly maintain, the edge of the material passing under the presser foot so that a uniform line of stitching with respect to said edge will be secured. The short arm 44 of the inverted J-shaped member is positioned in the slot 38 and engages the surface of the toe 36. The bridge element 45 of the inverted J-shaped member is disposed on the top of the toe 36. In the preferred form, the inverted J-shaped member is of a size so that it will snugly fit on to the toe 36, whereby the leg 42 will be secured in position and not move during its operation.

As shown in Figures 1, 2, 3 and 4, a folder 48 is provided in advance of the presser foot 20. The folder 48 is provided with a slot 50 extending longitudinally thereof and is adapted to receive the raw edges 52 of the seamed material 54, the raw edges 52 extending inwardly of the folder 48. At the entrance end, the folder 48 is curved in cross-section and may flare outwardly, as shown in Figure 4, to permit easy introduction of the material in the folder. The folder 48 at its exit end is substantially triangular in cross-section, as shown in Figure 7. Intermediate the entrance end and the exit end, the folder 48 is so constructed as to gradually assume the exit cross-section. The diameter of the folder 48 at its entrance end and the altitude of the triangular cross-section at the exit end may be of any suitable dimensions whereby the folder is adapted to

receive and operate on seamed materials in which the raw edges may be of various widths depending on the trimming operation.

The folder 48 is secured to one end of an arm 56, as by soldering, the other end of the arm 56 being adjustably (rotatably and slidably) mounted and fastened in a longitudinal bore in a holder 58 by means of a set screw 60. By moving the arm 56 in the holder 58 in the desired longitudinal direction and securing the same in the desired adjusted position, the folder 48 may be adjusted longitudinally with respect to the presser foot 20, the set screw 60 serving to secure the arm 56 in the adjusted position. By rotating the arm 56, the folder may be adjusted vertically with respect to the presser foot 20. In the preferred form shown, the folder 48 is positioned at an angle to the horizontal plane as shown and the exit end of the folder 48 is positioned in close proximity to the presser foot 20, though, if desired, the folder 48 may be positioned a greater or lesser spaced distance from the presser foot.

The holder 58 is pivotally mounted adjacent its rear end on a screw 62 carried by a block 64 on a bracket 66, the bracket 66 being secured by means of screws 68 to the work support 12 at the rear of the machine opposite to the operator. The holder 58 is provided with a slot 70 which cooperates with a screw 72 and whereby the holder 58 may be securely locked in position. When it is desired to remove the folder 48 and render it ineffective so that the machine may be used for normal sewing, the screw 72 is loosened and the holder 58 moved in a direction, clockwise in Figure 1, about the pivot 62. To maintain the holder 58 in inoperative position, there is provided a spring 74, one end of which is secured in any suitable manner, as by screws 76, to the block 64. The other end of the spring 74 is free and engages the rear end 78 of the holder. Thus, when the holder 58 is moved into inoperative position, as previously mentioned, the free end of the spring 74 will engage the end 78 of the holder and maintain it in the open position.

The arm 56 is of a design (curved) whereby upon the rotation thereof about its longitudinal axis, the folder 48 may be positioned vertically, and preferably angularly, with respect to the presser foot 20. Means are also provided to permit quick, fine horizontal adjustment of the folder 48 with respect to the presser foot 20. In the illustrative form shown, the bracket 66 is provided with an upstanding lug 80 which is provided adjacent the upper extremity thereof with a manually-controlled screw 82 which is adapted to bear on the holder 58, as at 84. By proper manipulation of the screw 82, the holder 58 may be given an adjustment in a transverse direction with respect to the presser foot.

It is to be noted that the folder 48, holder 58 and the bracket 66 are so mounted that none of these elements will interfere with the work as it passes through the machine.

In operation, two pieces of fabric 54 are seamed together by a line of stitching 86 on the right side thereof and trimmed to provide the raw edges 52. The thus-seamed material is then introduced into the entrance end of the folder 48 with the raw edges 52 and the line of stitching 86 in the interior thereof, as shown in Figure 5. As the material is fed through the machine by the feed dogs 24 and the presser foot 20 cooperating therewith, the material assumes the position shown in Figure 7, and, when the material leaves the folder 48, it is folded about the seam so that the raw edges 52

and the stitching 86 will be disposed between an upper ply 88 and a lower ply 90 formed by the material 54, and as shown in Figure 9. In this condition, the folded material is fed and received beneath the presser foot, the exposed edge of the folded material engaging the inner surface of the guiding member 42 of the J-shaped member. As the material in this condition is fed through the machine, it passes through the path of the needle 16 and is stitched thereby. It will be noted that the needle 16 penetrates both plies 88 and 90 of the material in close spaced proximity to the extremities of the raw edges 52, whereby the raw edges 52 and the stitching 86 are concealed between the plies 88 and 90. The stitching operation just described produces the line of stitching designated by the reference numeral 92. The plies 88 and 90 are then opened up, as shown in Figure 10, and finally the seamed material is pressed to produce the article shown in Figure 11.

If desired, the attachment may be mounted on a standard sewing machine head which is also provided with a knife for trimming the seam produced therein. When such a machine is used during the first operation, a normal standard presser foot is used in place and stead of the presser foot 20 hereinbefore described, and the folder 48 is moved into inoperative position as previously described. After the material has thus been seamed and the seam trimmed, the standard presser foot is removed and the presser foot 20, hereinbefore fully described, is substituted in place and stead of the normal standard presser foot. The folder 48 is then, by proper movement of the holder 58, positioned in advance of the presser foot 20 and adjusted into the proper and desired position with respect to the presser foot, as previously described.

From the foregoing, it is clear that the instant invention provides a sewing machine attachment which may be secured to any standard sewing machine without in any way mutilating or damaging said machine, and that when it is not desired for use it may be wholly removed or it may be rendered inoperative. The sewing machine attachment is so designed and constructed that it will produce a uniform line of stitching equally distant from the edge of the product, thereby resulting in a French seam of marked beauty and uniformity.

Though in the specific embodiment described herein the folder 48 is mounted in the holder 58 carried by the bracket secured adjacent to the back of the machine, the invention is not restricted thereto nor to the specific mounting of the folder 48, since it will be obvious to a person skilled in the art that the folder 48 may be adjustably positioned on another part of the machine and indeed on the machine head. Likewise, the invention is not restricted to the specific construction of the J-shaped member of the presser foot 20, since it will be obvious to a person skilled in the art that another guiding member having the function of the member 42 may be used.

Since it is obvious that various changes and modifications may be made in the above description without departing from the nature or spirit thereof, this invention is not restricted thereto except as set forth in the appended claims.

I claim:

1. A sewing machine comprising a reciprocating needle, feed dogs, a slotted presser foot cooperating with said feed dogs, a folder in advance of said presser foot to fold a seamed material

about the seam therein so that the stitching and the raw edges of the material adjacent the seam will be disposed between an upper and lower ply formed by the materials joined by the seam and present the thus-folded material to the presser foot and for stitching by the needle through at least the upper and lower plies, said folder having a slot extending longitudinally thereof to receive the raw edges and the line of stitching of a seamed material, the upper and lower plies extending outwardly from the slot being positioned over and under the folder respectively, said folder having its exit end substantially triangular in cross-section, and a substantially inverted J-shaped member disposed on one toe of said presser foot, the long leg of said inverted J-shaped member being positioned to engage the exposed edge of the folded material passing beneath said toe and maintain the same in uniform laterally spaced relationship with respect to the path of travel of the needle whereby stitching of the folded material at a uniform distance from the edge is secured as the material is fed through the path of the needle of the machine, the short leg of said inverted J-shaped member being positioned in the slot of the presser foot and engaging the inner surface of the toe on which said inverted J-shaped member is positioned.

2. A sewing machine comprising a reciprocating needle, feed dogs, a slotted presser foot cooperating with said feed dogs, a folder in advance of said presser foot to fold a seamed material about the seam therein so that the stitching and the raw edges of the material adjacent the seam will be disposed between an upper and lower ply formed by the materials joined by the seam and present the thus-folded material to the presser foot and for stitching by the needle through at least the upper and lower plies, said folder having a slot extending longitudinally thereof to receive the raw edges and the line of stitching of a seamed material, the upper and lower plies extending outwardly from the slot being positioned over and under the folder respectively, said folder having its exit end substantially triangular in cross-section, means to adjust the position of the folder with respect to said presser foot, and a substantially inverted J-shaped member disposed on one toe of said presser foot, the long leg of said inverted J-shaped member being positioned to engage the exposed edge of the folded material passing beneath said toe and maintain the same in uniform laterally spaced relationship with respect to the path of travel of the needle whereby stitching of the folded material at a uniform distance from the edge is secured as the material is fed through the path of the needle of the machine.

3. A sewing machine comprising a reciprocating needle, feed dogs, a slotted presser foot cooperating with said feed dogs, a folder in advance of said presser foot to fold a seamed material about the seam therein so that the stitching and the raw edges of the material adjacent the seam will be disposed between an upper and lower ply formed by the materials joined by the seam and present the thus-folded material to the presser foot and for stitching by the needle through at least the upper and lower plies, said folder having a slot extending longitudinally thereof to receive the raw edges and the line of stitching of a seamed material, the upper and lower plies extending outwardly from the slot being positioned over and under the folder respectively, said folder

having its exit end substantially triangular in cross-section, means to adjust the position of the folder with respect to said presser foot, and a substantially inverted J-shaped member disposed on one toe of said presser foot, the long leg of said inverted J-shaped member being positioned to engage the exposed edge of the folded material passing beneath said toe and maintain the same in uniform laterally spaced relationship with respect to the path of travel of the needle whereby stitching of the folded material at a uniform distance from the edge is secured as the material is fed through the path of the needle of the machine, the short leg of said inverted J-shaped member being positioned in the slot of the presser foot and engaging the inner surface of the toe on which said inverted J-shaped member is positioned.

4. A sewing machine comprising a reciprocating needle, feed dogs, a presser foot cooperating with said feed dogs, a bracket secured to the work support of said machine, a holder pivotally mounted on said bracket, an arm rotatably and slidably positioned in said holder, means to secure said arm in adjusted position in said holder, means carried by said arm to fold a seamed material longitudinally about the seam therein so that the stitching and raw edges of the material adjacent the seam will be disposed between an upper and lower ply formed by the materials joined by the seam, said arm being adapted to dispose the folding means in operative position in advance of said presser foot, means for producing a small horizontal movement of said holder and thereby produce a fine adjustment of said folder relative to said presser foot, and means to engage the exposed edge of the folded material and maintain the same in uniform laterally spaced relationship with respect to the path of travel of the needle whereby stitching of the folded material at a uniform distance from the edge is secured as the material is fed through the path of the needle of the machine.

5. A sewing machine comprising a reciprocating needle, feed dogs, a presser foot cooperating with said feed dogs, a bracket secured to the work support of said machine, a holder pivotally mounted on said bracket, a curved arm rotatably and slidably positioned in said holder, means to secure said arm in adjusted position in said holder, a folder carried by said arm to fold a seamed material longitudinally about the seam therein so that the stitching and raw edges of the material adjacent the seam will be disposed between an upper and lower ply formed by the materials joined by the seam, said folder having a slot extending longitudinally thereof to receive the raw edges and the line of stitching of a seamed material, the upper and lower plies extending outwardly from the slot being positioned over and under the folder respectively, said folder having its exit end substantially triangular in cross-section, said arm being adapted to dispose the folding means in operative position in advance of said presser foot, and means on the presser foot to engage the exposed edge of the folded material passing beneath said presser foot and maintain the same in uniform laterally spaced relationship with respect to the path of travel of the needle whereby stitching of the folded material at a uniform distance from the edge is secured as the material is fed through the path of the needle of the machine.

6. A sewing machine comprising a reciprocating needle, feed dogs, a slotted presser foot coop-

erating with said feed dogs, a bracket secured to the work support of said machine, a holder pivotally mounted on said bracket, an arm rotatably and slidably positioned in said holder, means to secure said arm in adjusted position in said holder, means carried by said arm to fold a seamed material longitudinally about the seam therein so that the stitching and raw edges of the material adjacent the seam will be disposed between an upper and lower ply formed by the materials joined by the seam, said arm being adapted to dispose the folding means in operative position in advance of said presser foot, and a substantially inverted J-shaped member disposed on one toe of said presser foot, the long leg of said inverted J-shaped member being positioned to engage the exposed edge of the folded material passing beneath said toe and maintain the same in uniform laterally spaced relationship with respect to the path of travel of the needle whereby stitching of the folded material at a uniform distance from the edge is secured as the material is fed through the path of the needle of the machine.

7. A sewing machine comprising a reciprocating needle, feed dogs, a slotted presser foot cooperating with said feed dogs, a bracket secured to the work support of said machine, a holder pivotally mounted on said bracket, an arm rotatably and slidably positioned in said holder, means to secure said arm in adjusted position in said holder, means carried by said arm to fold a seamed material longitudinally about the seam therein so that the stitching and raw edges of the material adjacent the seam will be disposed between an upper and lower ply formed by the materials joined by the seam, said arm being adapted to dispose the folding means in operative position in advance of said presser foot, and a substantially inverted J-shaped member disposed on one toe of said presser foot, the long leg of said inverted J-shaped member being positioned to engage the exposed edge of the folded material and maintain the same in uniform laterally spaced relationship with respect to the path of travel of the needle whereby stitching of the folded material at a uniform distance from the edge is secured as the material is fed through the path of the needle of the machine, the short leg of said inverted J-shaped member being positioned in the slot of the presser foot and engaging the inner surface of the toe on which said inverted J-shaped member is positioned.

8. A sewing machine comprising a reciprocating needle, feed dogs, a presser foot cooperating with said feed dogs, a bracket secured to the work support of said machine, a holder pivotally mounted on said bracket, an arm rotatably and slidably positioned in said holder, means to secure said arm in adjusted position in said holder, means carried by said arm to fold a seamed material longitudinally about the seam therein so that the stitching and raw edges of the material adjacent the seam will be disposed between an upper and lower ply formed by the materials joined by the seam, said arm being adapted to dispose the folding means in operative position in advance of said presser foot or upon movement of said holder about its pivot in inoperative position as desired, a spring engaging the holder and adapted to substantially lock it in position when said holder disposes said arm in inoperative position, and means to engage the exposed edge of the folded material passing beneath said presser foot and maintain the same in uniform lat-

erally spaced relationship with respect to the path of travel of the needle whereby stitching of the folded material at a uniform distance from the edge is secured as the material is fed through the path of the needle of the machine.

9. A sewing machine comprising a reciprocating needle, feed dogs, a presser foot cooperating with said feed dogs, a bracket secured to the work support of said machine, a holder pivotally mounted on said bracket, a curved arm rotatably and slidably positioned in said holder, means to secure said arm in adjusted position in said holder, a folder carried by said arm to fold a seamed material longitudinally about the seam therein so that the stitching and raw edges of the material adjacent the seam will be disposed between an upper and lower ply formed by the materials joined by the seam, said arm being adapted to dispose the folding means in operative position in advance of said presser foot or upon movement of said holder about its pivot in inoperative position as desired, a spring engaging the holder and adapted to substantially lock it in position when said holder disposes said arm in inoperative position, and means on the presser foot to engage the exposed edge of the folded material passing beneath said presser foot and maintain the same in uniform laterally spaced relationship with respect to the path of travel of the needle whereby stitching of the folded material at a uniform distance from the edge is secured as the material is fed through the path of the needle of the machine.

10. A sewing machine comprising a reciprocating needle, feed dogs, a slotted presser foot cooperating with said feed dogs, a bracket secured to the work support of said machine, a holder pivotally mounted on said bracket, an arm rotatably and slidably positioned in said holder, means to secure said arm in adjusted position in said holder, a folder carried by said arm to fold a seamed material longitudinally about the seam therein so that the stitching and raw edges of the material adjacent the seam will be disposed between an upper and lower ply formed by the materials joined by the seam, said arm being adapted to dispose the folding means in operative position in advance of said presser foot or upon movement of said holder about its pivot in inoperative position as desired, a spring engaging the holder and adapted to substantially lock it in position when said holder disposes said arm in inoperative position, and a substantially inverted J-shaped member disposed on one toe of said presser foot, the long leg of said inverted J-shaped member being positioned to engage the exposed edge of the folded material passing beneath said toe and maintain the same in uniform laterally spaced relationship with respect to the path of travel of the needle whereby stitching of the folded material at a uniform distance from the edge is secured as the material is fed through the path of the needle of the machine.

11. A sewing machine comprising a reciprocating needle, feed dogs, a slotted presser foot cooperating with said feed dogs, a bracket secured to the work support of said machine, a holder pivotally mounted on said bracket, an arm rotatably and slidably positioned in said holder, means to secure said arm in adjusted position in said holder, a folder carried by said arm to fold a seamed material longitudinally about the seam therein so that the stitching and raw edges of the material adjacent the seam will be disposed between an upper and lower ply formed by the

materials joined by the seam, said folder having a slot extending longitudinally thereof to receive the raw edges and the line of stitching of a seamed material, the upper and lower plies extending outwardly from the slot being positioned over and under the folder respectively, said folder having its exit end substantially triangular in cross-section, said arm being adapted to dispose the folding means in operative position in advance of said presser foot or upon movement of said holder about its pivot in inoperative position as desired, a spring engaging the holder and adapted to substantially lock it in position when said holder disposes said arm in inoperative position, and a substantially inverted J-shaped member disposed on one toe of said presser foot, the long leg of said inverted J-shaped member being positioned to engage the exposed edge of the folded material passing beneath said toe and maintain the same in uniform laterally spaced relationship with respect to the path of travel of the needle whereby stitching of the folded material at a uniform distance from the edge is secured as the material is fed through the path of the needle of the machine, the short leg of said inverted J-shaped member being positioned in the slot of the presser foot and engaging the inner surface of the toe on which said inverted J-shaped member is positioned.

12. A sewing machine attachment adapted to be secured to a sewing machine having a reciprocating needle, feed dogs and a presser foot bar, said attachment comprising a folder to fold a seamed material about the seam therein so that the stitching and raw edges of the material adjacent the seam will be disposed between an upper and lower ply formed by the materials joined by the seam, said folder having a slot extending longitudinally thereof to receive the raw edges and the line of stitching of a seamed material, the upper and lower plies extending outwardly from the slot being positioned over and under the folder respectively, said folder having its exit end substantially triangular in cross-section, a slotted presser foot to be positioned on said presser foot bar, said folder to be positioned in advance of said presser foot, and a substantially inverted J-shaped member disposed on one toe of said presser foot, the long leg of said inverted J-shaped member being positioned to engage the exposed edge of the folded material passing beneath said toe and maintain the same in uniform laterally spaced relationship with respect to the path of travel of the needle whereby stitching of the folded material at a uniform distance from the edge is secured as the material is fed through the path of travel of the needle of the machine.

13. A sewing machine attachment adapted to be secured to a sewing machine having a reciprocating needle, feed dogs and a presser foot bar, said attachment comprising a folder to fold a seamed material about the seam therein so that the stitching and raw edges of the material adjacent the seam will be disposed between an upper and lower ply formed by the materials joined by the seam, said folder having a slot extending longitudinally thereof to receive the raw edges and the line of stitching of a seamed material, the upper and lower plies extending outwardly from the slot being positioned over and under the folder respectively, said folder having its exit end substantially triangular in cross-section, a slotted presser foot to be positioned on said presser foot bar, said folder to

be positioned in advance of said presser foot, and a substantially inverted J-shaped member disposed on one toe of said presser foot, the long leg of said inverted J-shaped member being positioned to engage the exposed edge of the folded material and maintain the same in uniform laterally spaced relationship with respect to the path of travel of the needle whereby stitching of the folded material at a uniform distance from the edge is secured as the material is fed through the path of travel of the needle of the machine, the short leg of said inverted J-shaped member being positioned in the slot of the presser foot and engaging the inner surface of the toe on which said member is positioned.

14. A sewing machine attachment adapted to be secured to a sewing machine having a reciprocating needle, feed dogs and a presser foot bar, said attachment comprising a folder to fold a seamed material about the seam therein so that the stitching and raw edges of the material adjacent the seam will be disposed between an upper and lower ply formed by the materials joined by the seam, said folder having a slot extending longitudinally thereof to receive the raw edges and the line of stitching of a seamed material, the upper and lower plies extending outwardly from the slot being positioned over and under the folder respectively, said folder having its exit end substantially triangular in cross-section, a slotted presser foot to be positioned on said presser foot bar, means to adjustably position said folder in advance of said presser foot and a substantially inverted J-shaped member disposed on one toe of said presser foot, the long leg of said inverted J-shaped member being positioned to engage the exposed edge of the folded material passing beneath said presser foot and maintain the same in uniform laterally spaced relationship with respect to the path of travel of the needle whereby stitching of the folded material at a uniform distance from the edge is secured as the material is fed through the path of travel of the needle of the machine.

15. A sewing machine attachment adapted to be secured to a sewing machine having a reciprocating needle, feed dogs and a presser foot bar, said attachment comprising a bracket to be secured to the work support of said machine, a holder pivotally mounted on said bracket, an arm adjustably secured in said holder, a folder carried by said arm to fold a seamed material longitudinally about the seam therein so that the stitching and raw edges of the material adjacent the seam will be disposed between an upper and lower ply formed by the materials joined by the seam, said folder having a slot extending longi-

tudinally thereof to receive the raw edges and the line of stitching of a seamed material, the upper and lower plies extending outwardly from the slot being positioned over and under the folder respectively, 5 said folder having its exit end substantially triangular in cross-section, a presser foot adapted to be positioned on said presser foot bar, said arm being adapted to position the folding means in operative position in advance of the 10 presser foot, and means on said presser foot to engage the exposed edge of the folded material passing beneath said presser foot and maintain the same in uniform laterally spaced relationship with respect to the path of travel of the needle 15 whereby stitching of the folded material at a uniform distance from the edge is secured as the material is fed through the path of the needle of the machine.

16. A sewing machine attachment adapted to 20 be secured to a sewing machine having a reciprocating needle, feed dogs and a presser foot bar, said attachment comprising a bracket to be secured to the work support of said machine, a holder pivotally mounted on said bracket, a curved arm rotatably and slidably positioned in 25 said holder, means to secure said arm in adjusted position in said holder, a folder carried by said arm to fold a seamed material longitudinally about the seam therein so that the stitching and 30 raw edges of the material adjacent the seam will be disposed between an upper and lower ply formed by the materials joined by the seam, said folder having a slot extending longitudinally thereof to receive the raw edges and the line of 35 stitching of a seamed material, the upper and lower plies extending outwardly from the slot being positioned over and under the folder respectively, said folder having its exit end substantially triangular in cross-section, a presser 40 foot adapted to be positioned on said presser foot bar, said arm being adapted to position the folding means in operative position in advance of the presser foot or upon movement of said holder about its pivot in inoperative position, a spring 45 engaging said holder and adapted to substantially lock it in position when said folder is in inoperative position, and means on said presser foot to engage the exposed edge of the folded material passing beneath said presser foot and maintain the same in uniform laterally spaced relationship 50 with respect to the path of travel of the needle whereby stitching of the folded material at a uniform distance from the edge is secured as the material is fed through the path of the needle 55 of the machine.

CHARLES SEAMAN.
